UNITED STATES PATENT OFFICE.

WILLIAM POPENDICK, OF DECATUR, MICHIGAN.

COLLAPSIBLE FORM FOR ARCHES.

1,284,766.

Specification of Letters Patent. Patented Nov. 12, 1918.

Application filed March 2, 1918. Serial No. 219,988.

To all whom it may concern:

Be it known that I, WILLIAM POPENDICK, a citizen of the United States, residing at Decatur, in the county of Van Buren and State of Michigan, have invented new and useful Improvements in Collapsible Forms for Arches, of which the following is a specification.

This invention relates to collapsible forms for arches, and the object is to provide a device for use in connection with the construction of arches of brick, stone, or concrete, and of practically any size required for a given purpose.

A further object is to provide a device, or form, for use in the construction of arches for buildings, bridges, and the like, which shall include a plurality of pivotally connected sections, with means connected with each pivotal mounting between adjacent sections and a bolt or the like passing through a slot in a third pivoted section, whereby adjustment and freedom of movement is secured.

A still further object is to provide a plurality of pivotally connected sections each having one side thereof cut away adjacent to its ends and each provided with a central longitudinal slot, the pivoted sections being reversely arranged with reference to one another, and a curved connecting bar secured to the pivotal mounting between two adjacent sections and having adjustable connection with a third section.

With the foregoing and other objects in view, the invention consists in the novel construction, combination and arrangement of elements hereinafter described and claimed.

Figure 1 is a view in elevation.

Fig. 2 is a plan view.

Figs. 3 and 4 show the links separated.

In carrying out my invention I provide a plurality of pivotally connected members 10 each constituting a voussoir and each of these members being similarly formed, but in the series constituting a given arch or form, the members are reversely arranged.

Each member 10 is cut away at the ends on one side of the body portion, these cut away portions being designated 12 and 13, and each member 10 is provided with a longitudinal slot 14 through which a pivotal member passes.

Members 10 are so arranged that the cut

away portions of adjacent members are located on opposite sides, thereby forming a substantially continuous structure, the respective side portions or surfaces of which are in the same plane throughout.

The members 10 are pivotally connected by means of pins or bolts 15 provided with heads and secured by means of nuts 16. A curved connecting bar 18 is pivotally secured at one end by one of the bolts 15 and extends to a point midway between the ends of an adjacent pivoted member 10 being there slidably retained in position by a bolt 20 passing through a slot 21 and secured by a nut 22. A plurality of bars 18 are provided on each side of the arch proper formed by the members 10, and these bars 18 are so arranged that they overlap, in a sense,—that is two adjacent bars 18 on a given side of the arch are located so that their approaching ends are intermediate of the ends of a given curved bar 18 on the opposite side of the structure formed by members 10. The elements 18 each comprise bars having deflected end portions 5, the sides of the bars being cut away longitudinally as shown at 6 providing for the heads of the bolts 15, the cooperation being shown in Fig. 2. The complete structure for a given arch may therefore be shaped to produce the curvature desired for a given arch, and when the required curvature is secured the nuts and bolts will of course be tightened for the purpose of making the elements rigid. By taking out any two bolts 90 the form may be collapsed.

The end members of the structure described are designated respectively 25 and 26, the upper ends having pivotal connection with adjacent members 10, and the curved bars 18 having connection with these end members in substantially the manner already described. A brace or chord for the arch is designated 28.

The construction above described may be inclosed within an arch member 30 of flat or band iron secured by means of any suitable radially extending device 31 engaged by the bolts passing through the voussoir members.

What is claimed is:

1. In a device of the class described, a plurality of pivotally connected members each provided with a substantially central longitudinal slot, a bar connected with the

- pivotal mounting of certain of said members, and a pin passing through the opposite end of the bar and through the slot of an adjacent pivoted member.
3. 2. In a device of the class described, a plurality of pivotally connected members, a pin effecting such pivotal connection, a third pivoted member secured to one of those first named, a pin for pivotally securing said third member, each of said members being provided with central longitudinal slots, a curved bar connected with the pivotal mounting of the members first named, means connecting the opposite end of the bar and passing through the slot of the third pivoted member, and a curved bar secured to the pivotal connection between the third member and one of the members
- 10
- 15
- first named and adapted for pivotal and slidable connection at its opposite end with 20 an adjacent or fourth pivoted member.
3. In a device of the class described, a plurality of pivotally connected members each being cut away on a given side at points adjacent to its ends, adjacent pivoted members being reversely arranged, pins for effecting the pivotal connection, each of said pivoted members being provided with a longitudinal slot, and a curved bar slidably connected with each pivoted member 25 at the slotted portion thereof and with the pivotal connection between adjacent pivoted members.

In testimony whereof I affix my signature.

WILLIAM POPENDICK.

Copies of this patent may be obtained for five cents each, by addressing the "Commissioner of Patents, Washington, D. C."
